UNITED STATES PATENT OFFICE.

CHARLES WHITE, OF EAST ORANGE, NEW JERSEY, ASSIGNOR TO WESTERN ELECTRIC COMPANY, INCORPORATED, OF NEW YORK, N. Y., A CORPORATION OF NEW YORK.

SIGNALING SYSTEM.

Application filed May 5, 1921. Serial No. 466,932.

To all whom it may concern:

Be it known that I, CHARLES WHITE, a citizen of the United States, residing at East Orange, in the county of Essex and State 5 of New Jersey, have invented certain new and useful Improvements in Signaling Systems, of which the following is a full, clear, concise, and exact description.

This invention relates to signaling systems having separate transmission circuits 10 for oppositely directed signals, commonly known as four-wire systems, and more particularly to such systems wherein means are provided at an intermediate station for the 15 operator or attendant to listen-in and to communicate thereover, if desired.

In ordinary telephone systems and in carrier wave signaling systems which terminate in two-wire low frequency telephone lines, 20 it has been customary to provide means for the operator or attendant to listen-in and, if need be, to communicate over the systems. For the purpose of listening-in on those systems a telephone receiver with suitable ap-

25 paratus is connected across the low frequency line by means of a monitoring key. For communication purposes a microphone circuit can be connected to the low frequency line in any suitable way, preferably 30 by means of a patching cord.

By this invention means is provided whereby an operator or attendant may listen in on a four-wire telephone line, or on a four-wire low frequency termination of a carrier 35 wave signaling system. Means is also provided whereby the operator or attendant may communicate over the system if desired.

One object of the invention is to provide 40 means for listening-in and communicating over a four-wire low frequency telephone line. Another object is to provide means of this kind at a four-wire termination of a carrier wave signaling system. Still another object is to provide a monitoring system 45 wherein the operator or attendant can listen-in on both pairs of the four-wire line simultaneously. A feature of the invention is the use of a conjugate transformer to accomplish the above results. Another feature 50 is the provision of a relay arrangement for automatically associating the microphone with the proper pair of the four-wire line

for talking and the receiver with the proper pair, for receiving when communicating over the system. Still another feature is the provision of a system which can be used for communicating either over a four-wire system or a two-wire system.

In one embodiment of the invention a carrier wave signaling system terminates in a 60 four-wire low frequency telephone line. By means of a key, a conjugate transformer or hybrid coil and a plug and jack arrangement, a telephone receiver and a microphone are adapted to be connected to the low frequency line. The arrangement is such that an operator or attendant may listen-in on both pairs of conductors simultaneously 65 without causing interference therebetween or he may communicate either over the carrier system or over the four-wire low frequency line. In order to insure that his receiver and microphone will each be connected to the proper pair of conductors, an automatic relay switching system is provided. Further 70 provision is made for using the same system in connection with a two-way carrier channel and its associated low frequency line.

The invention will now be described more in detail with reference to the accompanying 80 drawings. Fig. 1 shows the preferred form of the invention as embodied in a four-wire carrier wave terminal station. Fig. 1^a illustrates a two-way carrier terminal with two-wire low frequency termination located at 85 the station of Fig. 1 with which the arrangement of Fig. 1 is adapted to be used. Fig. 2 shows another embodiment also adapted for use in a four-wire system. It is to be understood that the detailed description does 90 not limit the invention to the precise embodiments illustrated.

Referring now to Fig. 1 of the drawing, a four-wire low frequency telephone line, comprising one pair of conductors 5 and 95 another pair 6, is connected by means of a carrier wave terminal station to a common transmission line ML. The conductors 5 terminate in a pair of jacks 7. The transmitting circuit TC of the carrier terminal 100 station terminates, on the low frequency side, in jacks 8 and, on the high frequency side, at the bridge connections of balanced transformer 9. A balancing network HFN,

to balance the main line ML, is also connected to the balanced transformer 9 in a well-known manner. Jacks 7 and 8 are connected together in such a way as normally to furnish a continuous circuit between conductors 5 and transmitting circuit TC. Conductors 6 terminate in jacks 10. Receiver circuit RC is connected, on the low frequency side, to jacks 11 and on the high frequency side to the series winding of the balanced transformer 9. Jacks 10 and 11 are so connected together that normally a continuous circuit is provided between conductors 6 and the receiver circuit RC.

The other end of the four-wire low frequency line 5-6 terminates in a two-wire ordinary telephone exchange or subscriber's station A. The conductors 5 and 6 are conjugately connected to station A through the balanced transformer 12 with its low frequency balancing network LFN. This is a well-known arrangement and needs no further description.

In the transmitting circuit TC is a modulator M, an oscillator O, a modulator band filter MBF, and an input transformer 15. The oscillator O functions as a source of carrier waves for this channel. The receiver circuit comprises a detector band filter DBF, a detector D, a detector amplifier DA, a low pass filter LPF and a transformer 16.

The modulator M, the oscillator O, the detector D and the detector amplifier DA may be of any suitable design, but preferably comprise three electrode thermionic vacuum discharge devices. The modulator band filter MBF and detector band filter DBF are broad band-pass filters of the general type described in Patents Nos. 1,227,113 and 1,227,114 to G. A. Campbell, May 22, 1917. These filters are adapted to pass a band of frequencies equal to the range of frequencies used in voice transmission located in the neighborhood of the carrier frequency used for transmission in this channel. The low pass filter LPF is also of the general Campbell type and is adapted to suppress currents having frequencies above the highest essential frequencies of voice currents and to transmit with substantially negligible attenuation currents of the highest essential voice frequency and of all lower frequencies.

Connections for additional transmitting channels are indicated by the dotted lines 16, and additional receiving channels by the dotted lines 17. Only one additional channel is shown, but any number may be inserted in a similar manner.

In the operation of this system a terminal station similar to the one illustrated is located at the distant end of the common line ML. The receiving circuit of that station is adapted to cooperate with the trans-

mitting circuit of the terminal illustrated, while the transmitting circuit of the distant station is adapted to cooperate with the receiving circuit of Fig. 1.

A message may be transmitted from the station A to the distant cooperating station as follows:

Voice currents originating at station A are transmitted by the balanced transformer 12 and conductors 5 through normally closed contacts of jacks 7 and 8 and the transformer 15 to the modulator M. In the modulator M carrier waves from the oscillator O are modulated by the incoming voice currents and transmitted from the modulator through the modulator band filter MBF and the balanced transformer 9 to the main line ML. Assuming now for purposes of description that the station of Fig. 1 is the cooperating distant station, the modulated carrier waves from the common line ML are transmitted to the receiving circuit RC by the balanced transformer 9 through the detector band filter DBF to the detector D. In the system illustrated both the modulated and unmodulated currents are transmitted to the common line ML and received therefrom. In the detector D the modulated and unmodulated currents are combined to produce the original voice currents which are amplified in the detector amplifier DA and transmitted through the low pass filter LPF, transformer 16, normally closed contacts of jacks 11 and 10, conductors 6 and the balanced transformer 12 to the station A.

In order to provide for monitoring or listening-in by the operator or attendant at the carrier terminal station, a monitoring key K and a conjugate transformer or hybrid coil 20 are used to associate a telephone receiver 26 with the low frequency conductors of each of the transmitting circuit TC and the receiving circuit RC. When key K is operated, conductors 21 bridged across the transmitting circuit TC are connected through the upper closed contacts (normally open) of key K and the transformer 22 to the series winding of hybrid coil 20. Conductors 23 which are bridged across the receiving circuit RC are connected through the lower closed contacts (normally open) of key K and the transformer 24 to the bridge terminals of hybrid coil 20. Relay 25 is operated by the operation of key K due to the closing of the energizing circuit of relay 25 at the lowest closed contact (normally open) of key K. This circuit may be traced from the ground side of battery 27, through battery 27, winding of relay 25, lowest closed contact (normally open) of key K to ground. The operation of relay 25 connects receiver 26 with the line terminals of hybrid coil 20 at the closed front contacts (normally open) 130

of relay 25. Across the opposite line terminals of hybrid coil 20 is connected an impedance 28 which balances the impedance of receiver 26. With the key K in its normal 5 position, receiver 26 and hybrid coil 20 are disconnected from the carrier terminal apparatus.

By means of the monitoring circuit just described an operator listening in at the 10 receiver 26 can hear what is going on on either the transmitting circuit TC or the receiving circuit RC, but due to the conjugacy of hybrid coil 20, current in conductors 21 has no effect upon conductors 23 15 and vice versa. Consequently, a monitoring system is provided for a four-wire low frequency telephone circuit whereby an operator may listen-in simultaneously on each pair of conductors without causing 20 interference between the pairs of conductors.

In order to provide for communication over the system by the operator or attendant, the apparatus now to be described is provided.

25 For receiving purposes, receiver 26 is connected to jacks 31 through the normally closed back contacts of relay 25, normally closed contacts of key KT and the normally closed back contacts of relay 32. For talking purposes, a microphone 33 is associated 30 with jacks 34 through an induction coil 35, normally closed contacts of ringing key RK and normally closed back contacts of relay 36. In order to provide for call signaling 35 by the operator, a source of ringing current 37 is adapted to be impressed upon the system by means of ringing key RK. A two-conductor cord 38, terminating in plugs 39 and 40 is adapted to patch the circuits terminating 40 in jacks 31 to those terminating in either jacks 7 or 8. The three-conductor cord 41, terminating in plugs 42 and 43 is adapted to patch the circuits terminating 45 in jacks 34 to those terminating in either jacks 10 or 11.

Relays 32 and 36 are provided to automatically interchange jacks 31 and 34 with respect to the receiver 26 and the microphone 33. In the normal position of relays 50 32 and 36, receiver 26 is connected to jacks 31, and microphone 33 to jacks 34 over the circuits hereinbefore traced. When relays 32 and 36 are actuated, receiver 26 is connected to jack 34 through the normally 55 closed back contacts of relay 25, normally closed contacts of key KT and the closed front contacts (normally open) of relay 32, while the microphone 33 is connected to jacks 31 through the induction coil 35, the 60 normally closed contacts of ringing key RK and the closed front contacts (normally open) of relay 36.

The operation of communicating from the carrier terminal station to the station A 65 will now be described. Jacks 31 and 7 are

patched together by means of cord 38 by the insertion of plugs 39 into jacks 7 and plugs 40 into jacks 31. Jacks 10 and 34 are patched together by means of cord 41 by the insertion of plugs 43 into jacks 10 and 70 plugs 42 into jacks 34. A message originating at station A is transmitted to receiver 26 through the conjugate transformer 12, conductors 5, tip connections of jacks 7 and 75 plugs 39, conductors of cord 38, tip connections of plugs 40 and jacks 31, normally closed back contacts of relay 32, normally closed contacts of key KT and normally closed back contacts of relay 25. A message originating at the carrier terminal station in microphone 33 is transmitted to station A through the induction coil 35, normally closed contacts of ringing key RK, 80 normally closed back contacts of relay 36, tip connections of jacks 34 and plugs 42, tip conductors of cord 41, tip connections of plugs 43 and jacks 10, conductors 6 and bridge connections of conjugate transformer 12. The insertion of plugs 39 in jacks 7 and 85 plugs 43 in jacks 10, disconnects the conductors 5 and 6 from the carrier transmitting circuit TC and receiving circuit RC respectively at the open contacts (normally closed) of jacks 7 and 10.

In the event that the operator at the carrier station wishes to communicate by means of carrier wave transmission over the main line ML instead of with the station A, plugs 39 are withdrawn from jacks 7 and inserted in jacks 8 and plugs 43 are withdrawn from jacks 10 and inserted in jacks 11. The insertion of plugs 43 in jacks 11 causes the 90 operation of relays 32 and 36 so that receiver 26 is now connected to the receiver circuit RC and the microphone 33, to the carrier transmitting circuit TC. The energizing circuits of relays 32 and 36 extend 95 from the ground side of batteries 44 and 45 respectively, through those batteries, windings of relays 32 and 36 in parallel to the 100 normally closed left-hand contact of key KT, through the sleeve contacts of jacks 34 and plugs 42, through the sleeve conductor of cord 41, the sleeve contacts of plugs 43 and jacks 11, and the resistance 105 46 to ground.

The message circuit between the carrier terminal station and a distant cooperating station may be traced as follows:

A message originating in the microphone 120 33, after passing through the induction coil 35, normally closed contacts of ringing key RK, closed front contacts (normally open) of relay 36, tip connections of jacks 31 and plugs 40, conductors of cord 38, tip connections of plugs 39 and jacks 8 and transformer 15, modulates the carrier current 125 from oscillator O. From the modulator M it passes through the band filter MBF and the conjugate transformer 9 as modulated 130

energy to the main line ML. Modulated energy incoming from the main line ML passes through the conjugate transformer 9 and detector band filter DBF to the detector D, where the originating voice currents are detected. After amplification by the detector amplifier DA, they pass through the low pass filter LPF, transformer 16, tip connections of jacks 11 and plugs 43, tip conductors of cord 41, tip connections of plugs 42 and jacks 34, closed front contacts (normally open) of relay 32, normally closed right-hand contacts of key KT, and normally closed back contacts of relay 25 to the receiver 26.

If the operator should by any chance interchange plugs 39 and 43 by inserting plugs 39 in jacks 11 and plugs 43 in jacks 8, relays 32 and 36 would not be operated since there would be no ground connection from the sleeve of jacks 8. Still the message circuit would be correct since the microphone 33 would be connected to the carrier transmitting circuit TC and the receiver 26 would be connected to the carrier receiver circuit RC. The transmitting circuit, under this condition, may be traced from the microphone 33, through the induction coil 35, the normally closed contacts of ringing key RK, normally closed back contacts of relay 36, the tip connections of jacks 34 and plugs 42, tip conductors of cord 41, tip connections of plugs 43 and jacks 8, which jacks constitute the terminal of the transmitting circuit TC. The receiving circuit may be traced from the receiver 26 through the normally closed back contacts of relay 25, the normally closed right-hand contacts of key KT, the normally closed back contacts of relay 32, tip connections of jacks 31 and plugs 40, conductors of cord 38, tip connections of plugs 39 and jacks 11, which jacks constitute the termination of the receiving circuit RC. In order to provide for communication from the carrier terminal station over a two-wire low frequency line or over a two-way carrier channel terminating on the low frequency side in a two-wire line, key KT is provided. Its use will be described hereinafter in connection with Fig. 1^a.

In Fig. 2, a modified system is provided whereby an operator or attendant at a carrier terminal station may communicate in either direction over the four-wire system of Fig. 1. Like reference characters in all of the figures are used to designate like elements.

The connections of relays 32 and 36 to jacks 31 and 34 in Fig. 2, are identical with the connections of these elements in Fig. 1. Instead of connecting the receiver directly to the armature contacts of relay 32 and the transmitter directly to the armature contacts of relay 36, an operator's subset com-

prising a microphone 51, a receiver 52 and an induction coil 53 are associated with the armature contacts of relays 32 and 36 through the conjugate transformer 50. The operator's subset is connected to one set of line terminals of the transformer 50 and is balanced by a network CN connected to the opposite pair of terminals. The direction in which transmission takes place through this circuit arrangement is shown by arrows. 75

When the arrangement of Fig. 2 is used with the transmission system of Fig. 1, jacks 31 and 34 are patched to jacks 7 and 10 or 8 and 11 in exactly the same manner as hereinbefore described and the results accomplished are entirely similar. Further detailed description of the connections and the operation of the system is therefore not required. 80

In Fig. 1^a is shown a two-way carrier wave transmission system terminating in a two-wire low frequency line whereby conversation may be carried on between an ordinary telephone subscriber's subset or telephone exchange B and a distant cooperating station over a common transmission line ML. The lines ML are separate physical lines which terminate at the same station where the carrier apparatus of Figs. 1 and 1^a are located. The station B is connected to the carrier terminal station by a line 54 terminating in jacks 55. The low frequency terminals of the transmitting circuit TC and receiver circuit RC are conjugately connected by means of the conjugate transformer 56 to the two-wire circuit terminating in jacks 57. Normally a continuous circuit is provided from the conjugate transformer 56 to the low frequency line 54 through the normally closed contacts of jacks 57 and 55. A low frequency network LFN to balance the low frequency line 54 is normally connected to the conjugate transformer 56 through the normally closed back contacts of relay 58. The elements in the carrier transmitting circuit TC and in the receiver circuit RC may be identical with those described in connection with Fig. 1 and are connected to the main line ML in an identical manner. 100

Let it be assumed now that an operator or attendant at the carrier terminal of Fig. 1 wishes to communicate with a party at station B. The key KT will be thrown to its operated position and jacks 34 will be patched to jacks 55 by the insertion of plugs 42 in jacks 34 and plugs 43, in jacks 55. The insertion of plugs 43 in jacks 55 disconnects the carrier terminal apparatus from the line 54 at the open contacts (normally closed) of jacks 55. The operation of key KT disconnects relays 32 and 36 from the sleeves of jacks 34 at the normally closed (now open) left-hand contact of key KT and connects relay 59 to the 110 115 120 125 130

5 sleeves of jacks 34. Relay 59 is not operated, however, since its energizing circuit is open at the sleeves of jacks 55. The function of relay 59 will be hereinafter described. The operation of key KT also disconnects receiver 26 from jacks 31 at the right-hand open contacts (normally closed) and connects the receiver 26 to the bridge points of the operator's telephone set 10 through the normally closed back contacts of relay 25 and the closed (normally open) right-hand contacts of key KT.

15 A message originating at station B reaches the receiver 26 over the line 54, tip connections of jacks 55 and plugs 43, tip conductors of cord 41, tip connections of plugs 42 and jacks 34, normally closed back contacts of relay 36, normally closed contacts of ringing key RK, normally closed back 20 contacts of relay 59, bridge connections of the operator's telephone set, right-hand closed contacts (normally open) of key KT and normally closed back contacts of relay 25. A message originating at microphone 25 33 reaches the station B through the induction coil 35 and the circuit just traced except that practically none of the current reaches the receiver due to the anti-side tone connection of the operator's telephone 30 set.

In order that the operator or attendant at the carrier telephone station of Fig. 1 may communicate over the two-way channel of the carrier terminal station of Fig. 1^a, 35 plugs 43 are withdrawn from jacks 55 and inserted in jacks 57. Due to this operation, relays 58 and 59 are operated by current in an energizing circuit which may be traced from the ground side of battery 60, through battery 60, winding of relay 59, left-hand closed contact (normally open) of key KT, sleeve contacts of jacks 34 and plugs 42, sleeve conductor of cord 41, sleeve contacts 40 of plugs 43 and jacks 57, winding of relay 58 to ground. The operation of relay 59 has the effect of inserting a resistance 62 in the lower conductor of the operator's telephone circuit by removing a short-circuit about the resistance 62 at the open contact 45 (normally closed) of relay 59 and connecting a resistance element 61 across this circuit at the closed front contact (normally open) of relay 59. Resistance elements 62 and 61 when so connected operate as an 50 artificial line of a certain length depending upon the values of the resistances 62 and 61. The operation of relay 58 substitutes a network MN to balance the operator's telephone circuit in place of the low frequency 55 network LFN which normally balances the low frequency line 54. The function of the artificial line is to reduce the effect upon the conjugate transformer 56 of impedance changes in the microphone 33 of the operator's telephone circuit and so to permit of 60

65 maintaining the required balance by means of a fixed network MN. By the substitution of network MN for the normally connected network LFN, a simple artificial line, such as is provided by the resistances 61 70 and 62, may be used.

75 While the invention has been described in connection with carrier current terminal stations, it is equally applicable to ordinary four-wire telephone circuits. Its application to such a circuit will be obvious to those skilled in the art from the description of its application to the low frequency four-wire termination of a carrier current telephone system and further description 80 will, therefore, not be given.

The scope of the invention is understood to be defined by the appended claims.

What is claimed is:

1. In a telephone system, a four-wire line, 85 a telephone receiver, a conjugate transformer, means to connect said receiver to said conjugate transformer, means to connect said conjugate transformer to the four-wire line, and means to cause connection 90 of the receiver to the conjugate transformer whenever the conjugate transformer is connected to the four-wire line.

2. In a telephone system, a four-wire line, 95 a telephone receiver, a conjugate transformer, a relay to connect said receiver to said conjugate transformer, and a key to connect the conjugate transformer to the four-wire line.

3. In a telephone system, a four-wire 100 line, a telephone receiver, a conjugate transformer, a relay to connect the receiver to the conjugate transformer, a key to connect the conjugate transformer to the four-wire line, and means to cause the operation 105 of the relay whenever the key is operated to connect the conjugate transformer to the four-wire line.

4. In a telephone system, a four-wire 110 line, a telephone receiver, a conjugate coil, means to connect the receiver to the conjugate coil, means to connect the conjugate coil to the four-wire line, means to operate the receiver-connecting means whenever the conjugate coil is connected to the four-wire 115 line, and an impedance connected to the conjugate coil to balance the telephone receiver.

5. In a telephone system, a telephone receiver, a conjugate coil, a relay to connect 120 the receiver to the conjugate coil, a key to connect the conjugate coil to the four-wire line, and an impedance connected to the conjugate coil to balance the telephone receiver.

6. In a telephone system, a telephone receiver, a conjugate coil, a relay to connect the telephone receiver to the conjugate coil when the relay is energized, a key adapted 125 when operated to connect the conjugate coil to the four-wire line, means to energize the 130

relay effective whenever the key is operated, and an impedance connected to the conjugate coil to balance the telephone receiver.

7. In a telephone system, a four-wire line comprising two pairs of conductors, a telephone receiver, a conjugate coil, a series winding for said conjugate coil, a bridge connection for said coil, means to connect the series winding to one pair of conductors, 10 means to connect the bridge winding to the other pair of conductors, and means to connect the receiver to the conjugate coil whenever the series winding and bridge connection of the conjugate coil are connected each 15 to a pair of conductors of the four-wire line.
8. In a telephone system, a four-wire line comprising two pairs of conductors, a telephone receiver, a conjugate transformer, a series winding for said transformer a bridge 20 connection for said transformer, means to connect the receiver to the conjugate transformer, and a key adapted to connect the series winding to one pair and the bridge connection to another pair of said four-wire line and to cause the connection of the 25 telephone receiver to the conjugate transformer.

9. In a telephone system, a four-wire line comprising two pairs of conductors, a telephone receiver, a conjugate transformer, a series winding and a bridge connection for said transformer, a relay adapted to connect the receiver to the conjugate transformer, and a key adapted to connect the 30 series winding and the bridge connection each to a pair of conductors of the four-wire line and to cause the energization of the relay to connect the receiver to the conjugate coil.

10. In a telephone system, a four-wire line comprising two pairs of conductors, a telephone receiver, a conjugate transformer, a series winding for said transformer, a bridge connection for said transformer, a 45 relay adapted to connect the receiver to the transformer, a key adapted to connect the series winding to one pair and the bridge connection to another pair of conductors of said four-wire line and to cause the actuation of the relay to connect the receiver to the conjugate transformer, and an impedance connected to the conjugate transformer to balance the telephone receiver.

11. In a telephone system, an intermediate station, a four-wire line comprising a pair of transmitting conductors and a pair of receiving conductors extending through said station, a telephone receiver and means comprising a hybrid coil and a key, adapted to connect the receiver simultaneously to both the transmitting and receiving conductors in such a way as to cause no interference between said conductors.

12. In a carrier current telephone system, 65 a carrier transmitting circuit, a carrier re-

ceiving circuit, means to connect said circuits to a common line, a telephone receiver, a conjugate transformer, means to conjugately connect said transformer to said transmitting and receiving circuits, and means to connect said receiver to said conjugate connecting means, operative whenever said conjugate connective means is actuated.

13. In a carrier current telephone system, 75 a carrier transmitting circuit, a carrier receiving circuit, means to connect said carrier circuits to a common line, a telephone receiver, a conjugate transformer, a series winding for said conjugate transformer, a bridge connection for said transformer, means to connect the series winding with the carrier transmitting circuit, means to connect the bridge connection with the carrier receiving circuit, and means to connect 80 the receiver with the conjugate transformer whenever the series winding and bridge connections are connected to the carrier transmitting circuit and the carrier receiving circuit respectively.

14. In a carrier current telephone system, a carrier transmitting circuit, a carrier receiving circuit, means to connect said circuits to a carrier transmission line, a telephone receiver, a conjugate transformer, a 95 series winding for said transformer, a bridge connection for said transformer, means adapted to connect the receiver to the conjugate transformer, and a key adapted to connect the series winding to the carrier 100 transmitting circuit and the bridge connection to the carrier receiving circuit respectively and to cause the actuation of the receiver-connecting means.

15. In a carrier current telephone system, 105 a carrier transmitting circuit, a carrier receiving circuit, a telephone receiver, a conjugate transformer, a series winding for said transformer and a bridge winding for said transformer, a relay adapted upon energization to connect the telephone receiver to the conjugate transformer, and a key adapted upon actuation to connect the series winding to the carrier transmitting circuit and the bridge connection to the carrier receiving circuit and to cause the energization of 110 said relay.

16. In a carrier current telephone system, a carrier transmitting circuit, a carrier receiving circuit, a telephone receiver, a conjugate transformer, a series winding for said transformer and a bridge connection for said transformer, a relay adapted upon energization to connect the telephone receiver to the conjugate transformer, a key 120 adapted upon actuation to connect the series winding to the carrier transmitting circuit and the bridge winding to the carrier receiving circuit and to cause the energization of 125 said relay, and an impedance connected 130

to the conjugate transformer to balance the telephone receiver.

17. In a telephone system, a four-wire line, a receiving circuit and a transmitting circuit at a monitoring station, means adapted to connect said receiving circuit and said transmitting circuit to the four-wire line, and automatic switching means to interchange the relative connection of said transmitting and receiving circuits.

18. In a telephone system, a four-wire line comprising two pairs of conductors, a receiving circuit and a transmitting circuit at a monitoring station, means adapted to connect said receiving circuit to either pair of conductors, means to connect said transmitting circuit to the other pair of said conductors, and automatic switching means to cause the receiving circuit and transmitting circuit to be connected respectively to the same pair of conductors independently of the way in which said receiving and transmitting connecting means are connected to said conductors.

19. In a telephone system, a four-wire line comprising two pairs of conductors, a receiving circuit and a transmitting circuit at a monitoring station, means to normally connect the receiving circuit to one pair of conductors and other means to normally connect the transmitting circuit to the other pair of conductors, and switching relays automatically energized to connect the receiving and transmitting circuits respectively to the same pair of conductors whenever the receiving and transmitting connecting means are interchanged.

20. In a telephone system, a four-wire line comprising two pairs of conductors, a receiving circuit and a transmitting circuit at a monitoring station, means to normally connect the receiving circuit to one pair of conductors and other means to connect the transmitting circuit to the other pair of conductors, and switching relays unaffected by the normal connection of said transmitting and receiving connecting means and adapted to interchange said transmitting and receiving circuits if the transmitter and receiving connecting means are reversely connected to said pairs of conductors.

21. In a telephone system, a four-wire line comprising two pairs of conductors, a receiving circuit adapted to be normally connected to one pair of conductors and a transmitting circuit adapted to be normally connected to the other pair of conductors, a pair of jacks normally connected to said transmitting circuit, another pair of jacks normally connected to said receiving circuit, means to connect said first-mentioned pair of jacks to one pair of conductors, means to connect said second pair of jacks to the other pair of conductors, and switching means between said jacks and said receiv-

ing and transmitting circuits to interchange said jacks with respect to said transmitting and receiving circuits whenever said connecting means are reversely connected to said pairs of conductors.

22. In a telephone system, a four-wire line comprising two pairs of conductors, a receiving circuit and a transmitting circuit at a monitoring station, a pair of jacks normally connected to said receiving circuit and a pair of jacks normally connected to said transmitting circuit, means to normally connect said receiving jack with one pair of conductors, means to normally connect said transmitting jack with the other pair of conductors, and a switching relay connected between said receiving and transmitting jacks and said receiving and transmitting circuits to interchange said jacks with respect to said receiving and transmitting circuits if said connecting means are reversely connected to said pairs of conductors.

23. In a telephone system, a four-wire line comprising a pair of conductors for transmitting and a second pair of conductors for receiving, a pair of cut-off jacks in said transmitting conductors, a pair of cut-off jacks in said receiving conductors, a receiving circuit and a transmitting circuit at a monitoring station, a pair of receiving jacks normally connected to said receiving circuit, a pair of transmitting jacks normally connected to said transmitting circuit, a patching cord adapted to normally connect said receiving jacks with said cut-off jacks in the transmitting pair of conductors, another patching cord adapted to normally connect said transmitting jacks with said cut-off jacks in the receiving pair of conductors, and switching means adapted to automatically interchange said receiving and transmitting jacks if said transmitting jacks are patched to said cut-off jacks in the transmitting pair of conductors.

24. In a telephone system, a four-wire line comprising a pair of conductors for transmitting and a second pair of conductors for receiving, a pair of cut-off jacks in said transmitting conductors, a pair of cut-off jacks in said receiving conductors, a receiving circuit and a transmitting circuit at a monitoring station, a pair of receiving jacks normally connected to said receiving circuit, a pair of transmitting jacks normally connected to said transmitting circuit, a patching cord adapted to normally connect said receiving jacks with said cut-off jacks in the transmitting pair of conductors, another patching cord adapted to normally connect said transmitting jacks with said cut-off jacks in the receiving pair of conductors, and switching means adapted to automatically interchange said receiving and transmitting jacks if said jacks are reversely connected to said pairs of conductors.

patched to the cut-off jacks in said transmitting and receiving pairs of conductors.

25. In a telephone system, a four-wire line comprising a pair of conductors for transmitting and a second pair of conductors for receiving, a pair of cut-off jacks in said transmitting conductors, a pair of cut-off jacks in said receiving conductors, a receiving circuit and a transmitting circuit at a monitoring station, a pair of receiving jacks normally connected to said receiving circuit, a pair of transmitting jacks normally connected to said transmitting circuit, a patching cord adapted to normally connect said receiving jacks with said cut-off jacks in the transmitting pair of conductors, another patching cord adapted to normally connect said transmitting jacks with said cut-off jacks in the receiving pair of conductors, and relay contacts connected in circuit between said receiving and transmitting jacks and said receiving and transmitting circuits adapted to interchange said transmitting and receiving jacks with respect to said transmitting and receiving circuits if said transmitting and receiving jacks are reversely connected to said cut-off jacks in the transmitting and receiving pairs of conductors.

26. In a carrier current telephone system, a carrier terminal station, a receiving circuit and a transmitting circuit at said terminal station, means adapted to connect said receiving and transmitting circuits to said carrier terminal station, and automatic switching means to interchange the connections of said transmitting and receiving circuits.

27. In a carrier current telephone system, a carrier transmitting circuit, a carrier receiving circuit, means to connect said circuits to a carrier transmission line, a receiving circuit and a transmitting circuit at a carrier terminal station, means to connect said receiving circuit to said carrier transmitting circuit, other means to connect said transmitting circuit to said carrier receiving circuit, and automatic switching means to interchange the connection of said receiving and transmitting circuits to said carrier transmitting and receiving circuits respectively.

28. In a carrier current telephone system, a carrier transmitting circuit, a carrier receiving circuit, a receiving circuit and a transmitting circuit for the use of the carrier attendant, means to connect said receiving circuit to said carrier transmitting circuit, means to connect said transmitting circuit to said carrier receiving circuit, and switching relays between said connecting means and said transmitting and receiving circuits adapted to interchange said transmitting and receiving circuits if said connecting means are reversely connected to said carrier transmitting and receiving circuits.

29. In a carrier current telephone system, a carrier terminal station, a carrier transmitting circuit, a carrier receiving circuit, a telephone transmitting circuit and a telephone receiving circuit all at said carrier terminal station, means to connect said telephone receiving circuit to said carrier transmitting circuit, other means adapted to connect said telephone transmitting circuit to said carrier receiving circuit, and switching relays adapted to interchange said transmitting and receiving circuits whenever said connecting means are reversely connected to said carrier transmitting and receiving circuits and operated whenever said connecting means are actuated.

30. In a carrier current telephone system, a carrier transmitting circuit, a carrier receiving circuit, a telephone receiving and a telephone transmitting circuit at the carrier terminal station, a pair of receiving jacks normally connected to said receiving circuit, a pair of transmitting jacks normally connected to said transmitting circuit, means to connect said receiving jacks to said carrier transmitting circuit, means adapted to connect said transmitting jacks to said carrier receiving circuit, and switching means between said jacks and said receiving and transmitting circuits adapted to interchange said receiving and transmitting circuits whenever said connecting means are reversely connected to the carrier transmitting and receiving circuits.

31. In a telephone system, a four-wire line, a two-wire line, a receiving circuit and a transmitting circuit at a monitoring station, means to connect said transmitting and receiving circuits to said four-wire line, means to connect said transmitting circuit to said two-wire line, and means operative upon such a connection to connect said receiving circuit to said transmitting circuit in operative relation with said two-wire line.

32. In a telephone system, a four-wire line, a two-wire line, receiving and transmitting circuits at a monitoring station, means to connect said receiving and transmitting circuits to the four-wire line, means to connect said transmitting circuit to said two-wire line, and a key adapted to connect said receiving circuit to said transmitting circuit in operative relation for telephone use with said two-wire line.

33. The method of signaling in a carrier wave system having a station terminating in a four-wire low frequency line, which method comprises transmitting signals over the low frequency line and listening-in simultaneously on each pair of conductors of the low frequency line without causing interference therebetween.

34. In a signaling system, two pairs of transmission conductors, means for impressing voice frequency signals upon each pair

of conductors, and means for listening-in simultaneously on each pair of conductors without causing interference therebetween.

35. In a signaling system, two pairs of voice current conductors, two pairs of carrier current conductors electrically connected to said first pairs of conductors respectively, means for impressing voice frequency signals upon each pair of conductors, and means for listening-in simultaneously on each pair of conductors without causing interference therebetween.

36. In a signaling system, two pairs of voice current conductors, two pairs of carrier current conductors, means electrically connecting said voice current pairs with said

carrier current pairs respectively, and means for monitoring a conversation in both directions simultaneously without mutual interference between said pairs carrying oppositely directed elements of said conversation.

37. In a signaling system, a terminal station, a second station, two pairs of voice frequency lines extending between said stations, a source of carrier current and a detecting means connected to said pairs of lines respectively at said second station, and means for monitoring a conversation in both directions simultaneously without mutual interference.

In witness whereof, I hereunto subscribe my name this 3rd day of May, A. D., 1921.

CHARLES WHITE.
